US00D915115S

(12) **United States Design Patent** (10) **Patent No.:** **US D915,115 S**
(45) **Date of Patent:** **** Apr. 6, 2021**

(54) **LETTER D CHAIR**

(71) Applicant: **SENDER'S CONSTRUCTION, LLC**,
Polk City, IA (US)

(72) Inventor: **Keith Nelson**, Grimes, IA (US)

(73) Assignee: **Sender's Construction, LLC**, Polk
City, IA (US)

(**) Term: **15 Years**

(21) Appl. No.: **29/652,555**

(22) Filed: **Sep. 17, 2020**

Related U.S. Application Data

(63) Continuation of application No. 29/652,144, filed on May 21, 2020, now Pat. No. Des. 899,835, and a continuation of application No. 29/723,752, filed on Feb. 10, 2020, now Pat. No. Des. 889,178, and a continuation of application No. 29/710,388, filed on Oct. 23, 2019, now Pat. No. Des. 878,129, and a continuation of application No. 29/693,047, filed on May 30, 2019, now Pat. No. Des. 868,519, and a continuation of application No. 29/677,264, filed on Jan. 18, 2019, now Pat. No. Des. 854,868, and a continuation of application No. 29/657,202, filed on Jul. 19, 2018, now Pat. No. Des. 846,931, and a continuation of application No. 29/622,770, filed on Oct. 19, 2017, now Pat. No. Des. 826,612, and a continuation of application No. 29/599,429, filed on Apr. 3, 2017, now Pat. No. Des. 807,092, and a continuation of application No. 29/572,875, filed on Aug. 1, 2016, now Pat. No. Des. 786,596, and a continuation of application No. 29/550,416, filed on Jan. 4, 2016, now Pat. No. Des. 765,452, and a continuation of application No. 29/531,933, filed on Jun. 30, 2015, now abandoned, and a continuation of application No. 29/475,661, filed on Dec. 5, 2013,
